UNITED STATES PATENT OFFICE.

JOHN M. YOUNG, OF BROOKLYN, NEW YORK, ASSIGNOR TO AMERICAN CAN COMPANY, OF NEW YORK, N. Y., A CORPORATION OF NEW JERSEY.

CONTAINER.

Application filed May 22, 1922. Serial No. 562,902.

This invention relates in general to side tearing strip key-opening cans, and has for a principal object the provision of means for guiding a key in the strip removing action.

5 A further and principal object of my invention is the provision of a can having an internal band adapted to extend up and form a neck upon which may be engaged the cover and edge flange after the tearing strip has 10 been removed after the manner of a slip cover in which the fastening means between the band and the body may cooperate with the cover seam to guide a key in its opening action.

15 In side tearing strip key-opening cans it is particularly desirable that the key be started in its tearing action accurately in order that the tearing on the score lines may be straight and evenly distributed. My invention 20 contemplates the insurance that this tearing will be accurate, easy and complete and to this end provision is made for the guiding of the key in its initial action and for the confinement of the lines of tear to the encircling score 25 lines setting off the tearing strip.

Numerous other objects and advantages of the invention will be apparent as it is better understood from the following description, which, taken in connection with the accompanying drawings, discloses a preferred embodiment thereof.

On the drawings,

Figure 1 is a side elevation of a can embodying my present invention;

25 Fig. 2 is an enlarged partial section through a side of the same and showing the action of the key in the initial tearing operation;

Fig. 3 is a side elevation of a band; and

40 Fig. 4 is a section taken substantially on the line 4—4 of Fig. 3 and showing the connection between the band ends.

The can shown on the drawing as a preferred embodiment of my present invention 45 comprises a body 11 having a bottom seamed to it at 12 and a top or cover 13 seamed to the body at 14. This cover seam in the present instance is the ordinary double seam well-known in the art and usually employed in process cans. Below the top a pair of parallel encircling score lines 15 are provided and between these are arranged diagonal score 50 lines 16 for directing the lines of tear back to the score lines 15 should there be a tend-

ency to tear inwardly in the removal of the 55 strip 17, i. e. the material between the score lines 15. A band 18 is arranged within the body and extends about the entire inner circumference of the can and from a point well below the lowermost score line 15 to closely 60 adjacent the cover 13. This band has its ends formed with a lock seam 19 as indicated in Figs. 3 and 4, this seam being located behind the outer face of the band in its finished form. The band is inserted in the body and 65 the body and band are pressed out at 21 just above the lower band edge. This forms an outwardly extending rim or rib of large diameter beneath the band. The outward extension of the can body at 21 resulting is 70 given a dimension substantially that of the outer circumference of the seam 14. Reference character 22 indicates a key adapted to engage a tongue 23 formed on the can body and extending beyond the side seam 24 in any 75 usual or preferred manner. It is, of course, intended that the key shall engage the tongue and then be rotated to cause the tongue to wind upon the key and severance progressively occur along the lines 15 so that the 80 strip 17 is finally removed and the cover, with the resulting flange part 25, may be removed and used as a slip cover upon the upper end of the band, the band also serving to confine the contents during and after the removal of 85 the strip. Since the outer diameter of the enlarged portion 21 of the body and the outer diameter of the seam are the same, these parts are adapted to form bearings for the key in the initial turning action and keep the key 90 in accurate position at the starting of and during the tearing action with resultant even tear upon both score lines 15, the diagonal score lines serving to return the lines of tear to the score lines 15 should departure tend to 95 occur at a later point in the removal of the strip. If the bead at 21 were small relative to the seam 14 the key would be inclined and would wind up the top edge of the tearing strip 17 faster than the bottom edge and a 100 transverse strain put on the strip which would sometimes tear across a diagonal score line 16 and the object of the improvement would be frustrated.

It is thought that the invention and many 105 of its attendant advantages will be understood from the foregoing description, and it will be apparent that various changes may be

made in the form and construction and arrangement of the parts without departing from the spirit and scope of the invention or sacrificing all of its material advantages, the 5 form hereinbefore described being merely a preferred embodiment thereof.

I claim:

1. A can, comprising a body having a cover seamed thereto and provided beneath said 10 cover with a strip set off by encircling score lines adapted to be torn away to remove the cover, said can having a bead beneath said score lines forming with the connection between the cover and body a circumferential 15 track adapted to guide a key employed for removing the strip, and an internal band secured within said body and extending above said score lines to provide a means for receiving the torn-away top of the can, said band 20 having its ends joined in a lock seam and being tightly secured within the can body, the outward projections of the cover seam and of the bead relative to the can wall being of the same extent so that the key is maintained

at right angles to the strip during the tearing 25 operation.

2. A can, comprising a body having a cover seamed thereto and provided beneath said cover with a strip set off by encircling score 30 lines adapted to be torn away to remove the cover, said can having a bead beneath said score lines forming with the connection between the cover and body a circumferential track adapted to guide a key employed for removing the strip, and an internal band secured within said body and extending above said score lines to provide a means for receiving the torn-away top of the can, said band 35 having its ends joined in a lock seam and having the lower edge thereof held in the bead of the can body with the lower end of said band formed and embraced in said bead, the outward projections of the cover seam and of the bead relative to the can wall 40 being of the same extent so that the key is maintained at right angles to the strip during the tearing operation.

JOHN M. YOUNG.
